UNITED STATES PATENT OFFICE.

THEODORE WENK, OF BROOKLYN, NEW YORK, AND EDWARD J. BROOKS,
OF EAST ORANGE, NEW JERSEY, ASSIGNORS TO E. J. BROOKS & CO., OF
NEW YORK, N. Y.

LEAD-AND-WIRE SEAL.

SPECIFICATION forming part of Letters Patent No. 340,394, dated April 20, 1886.

Application filed February 13, 1886. Serial No. 191,851. (No model.)

To all whom it may concern:

Be it known that we, THEODORE WENK and EDWARD J. BROOKS, citizens of the United States, residing, respectively, at Brooklyn, in the State of New York, and at East Orange, in the State of New Jersey, have invented a new and useful Improvement in Lead-and-Wire Seals, of which the following is a specification.

10 This invention relates to that class of seals for securing the doors of railway freight-cars and for like uses, which are fastened by compressing a seal-disk of "lead" upon the ends of a flexible shackle of "wire," after passing 15 the shackle through a pair of staples, or otherwise applying it.

The present invention consists, first, in a shackle of single wire provided at or near one or each extremity with a solid circumferential anchoring-enlargement integral therewith and of conical shape, with the base of the cone opposed to withdrawal, whereby the insertion of the shackle ends and the compression of the lead around them are facilitated, and effective 20 annular withdrawal resisting shoulders are formed; and, further, in a seal-disk having a pocket or cell in an otherwise solid eccentric body portion to receive the threading end or each threading end of the shackle, the entrance 25 to said cell being at the upper edge of the disk, and a peripheral groove or recess at the bottom and sides of the disk, whereby access to said cell in threading the seal is facilitated and the perfect solidification of the lead around 30 and above the anchoring devices at the pressing 35 operation is insured, while at the same time a large-faced and easily-compressed seal-disk is formed.

A sheet of drawings accompanies this specification as part thereof.

Figure 1 of these drawings is an elevation of the shackle of our seal unbent or "straight." Fig. 2 is an elevation of the completed seal straight, with the shackle partly in section. 45 Fig. 2^x is an edge view of the disk end. Figs. 3 and 4 are sectional face views of the seal as applied to a pair of car-door staples, with appended cross-sections, respectively showing the same as it appears before and after it is

pressed. Figs. 5 and 6 are sectional face views 50 of seals ready for the press, illustrating modifications; and Fig. 7 is an elevation of another seal straight, illustrating an additional modification.

Like letters of reference indicate corresponding parts in the several figures.

In the preferred embodiment of our joint invention, illustrated by Figs. 1 to 4, inclusive, our seal is composed of a flexible metallic shackle, A, of iron, copper, or other suitable wire, and a recessed seal-disk, B, of lead or equivalent soft metal. The shackle A has at or near each extremity a solid circumferential anchoring-enlargement, a, integral with the wire, projecting beyond its periphery and 60 formed of a conical shape, an annular shoulder being formed by its large end, while it tapers therefrom toward the adjacent extremity of the wire, for purposes hereinbefore set forth. One end of the shackle A, with its said anchoring-enlargement, is permanently united 65 with the disk B by casting the latter thereon, as represented by Figs. 2, 2^x, and 3. This "cast-in" end, or that portion of it within the disk, lies within an eccentric body portion, b, 70 of the disk B, as clearly shown in Fig. 3. For the reception of the other end of the shackle A, a pocket or cell, c, is formed within said body portion b, having its entrance conveniently exposed at the upper edge of the disk; 75 otherwise this body portion of the disk is solid, as aforesaid. Beyond it the sides and bottom of the disk are extended, being lightened by a deep peripheral groove or recess, r. (Best seen in Figs. 2^x and 3.) Preferably 80 said recess r does not communicate at all with said cell c, and consequently after the seal is pressed access to the anchoring device cannot be had by reopening said recess; but apart 85 from this, by the location of the recess as aforesaid we insure such solidification of the said body portion of the disk around and above the anchoring device at the pressing operation as to preclude withdrawal of the threaded end, and there can be no access to it laterally, nor 90 so as to refasten the wire after breaking it.

In the modification illustrated by Fig. 5 the shackle A² is not cast in, and the seal-disk

B^2 has a pair of cells, $c c$, to receive both shackle ends with their anchoring-enlargements a , as shown in the figure, preparatory to the pressing operation.

- 5 In the modification illustrated by Fig. 6 the shackle A^3 is provided with "detector-enlargements" d above its anchoring-enlargements a , to indicate the character of the wire to seal inspectors. This provision may obviously be used in cast-in seals, as well as in the other kind represented by the disk B^3 in the figure, and may be confined to the threaded end of the shackle, and the detector-enlargements may be of any shape with equal effect.
- 15 In the modification illustrated by Fig. 7 the cast-in end of the shackle A^4 is provided with "anchoring-indentations" i , according to Mr. Brooks's invention, patented June 27, 1876, illustrating the employment of any known anchoring device on the cast-in end of the shackle. The disk B^4 may be identical with said disk B .

In either form of the seal proportions and immaterial details of shape may be varied without departure from our invention. Known styles of soft-metal seal-disks may be used in connection with our shackle-wire without wholly losing the advantages of the latter, and our said seal-disk may be used with its distinctive advantages in greater or less degree, in connection with other styles of shackles; but in combination with each other, as shown, our said shackle and disk are believed to produce their said advantages most fully.

The seal, in either form, goes to the market with its shackle straight, as represented in Figs. 1, 2, 2^x, and 7. It is applied in customary manner by passing the shackle through a pair of car-door staples, C, for example. The shackle is then bent, and its free end or ends are "threaded" or inserted into the disk, as shown in Figs. 3, 5, and 6. In this operation the conical shape of the anchoring-enlargements a on the free or threading ends of the shackle, and the exposure of the entrances to the cells c at the upper edge of the seal disk, facilitate

threading, while the closed bottoms of the cells stop said enlargements within the seal-disk in proper position. A seal-press is now applied to the disk, and the seal is pressed, 50 as illustrated by Fig. 4. In this operation the sharp peripheral edges of the conical anchoring-enlargements a cut the lead, so as to facilitate its solidification around and above them, and such solidification is insured by the relative location of the body portion b and peripheral recess r , as aforesaid, while subsequent to the pressing or fastening operation said anchoring-enlargements resist and prevent withdrawal of either shackle end 55 provided therewith by surrounding the shackle end with an effective annular shoulder, as best seen in said Fig. 4.

Having thus described our said improvement in lead-and-wire seals, we claim as our 60 joint invention and desire to patent under this specification—

1. A shackle-wire having one or each end provided with a solid circumferential anchoring-enlargement of conical shape, forming an 70 annular withdrawal resisting shoulder, and tapering therefrom toward the adjacent extremity of the wire, in combination with a compressible soft-metal seal-disk having an opening to admit said anchoring-enlargement, 75 substantially as herein specified.

2. In a lead-and-wire seal, a seal-disk having an eccentric body portion extending upward to the upper edge of the disk provided for the reception of one or each shackle end, 80 with a cell, the entrance to which is exposed at the upper edge of said disk, said body portion being otherwise solid and constructed with a peripheral groove or recess in its extended bottom and lateral edges, substantially 85 as herein specified.

THEODORE WENK.
EDWARD J. BROOKS.
